UNITED STATES PATENT OFFICE.

PAUL A. GSTALDER, OF PITTSBURGH, PENNSYLVANIA, ASSIGNOR TO THE OHIO VARNISH COMPANY, OF CLEVELAND, OHIO, A CORPORATION OF OHIO.

GRAINING TOOL.

Application filed March 17, 1922. Serial No. 544,400.

To all whom it may concern:

Be it known that I, PAUL A. GSTALDER, a citizen of the United States, residing at Pittsburgh, in the county of Allegheny and State of Pennsylvania, have invented a certain new and useful Improvement in Graining Tools, of which the following is a full, clear, and exact description, reference being had to the accompanying drawings.

10 This invention relates to graining tools and is particularly concerned with a form of tool adapted to produce a grained structure closely simulating the grain of various woods.

15 The general object of this invention is to provide an improved graining tool. Graining tools usually comprise a handle portion and a curved bottom portion on which a graining pad is secured. This pad is usually of rubber or similar material and is provided with raised ribs thereon. In operation, such a tool is moved along the material to be grained and is simultaneously given a rocking motion. This results in forming 20 lines on the distemper coat which simulate very closely the actual grain of wood.

25 In producing grained surfaces, it is desirable that the material be applied in a somewhat irregular manner so that the lines will not be sharply defined and thus the resemblance of the grained article to the original material be not lost.

30 A suitable device whereby the above objects may be accomplished will be described in the following specification, taken in connection with the accompanying drawings wherein Fig. 1 is a perspective view of a graining tool embodying the features of my invention; Fig. 2 is an end view of the graining tool and Fig. 3 is a plan view of the 35 graining pad.

40 One embodiment of my graining tool is illustrated in Fig. 1 wherein the tool is shown as comprising a member 10 which 45 may be made of sheet metal and which is bent to form a substantially cylindrical handle portion 11 which merges by means of a curved portion 12 of rather short radius, with a bowed portion 13. This bowed portion which is of relatively large radius, in 50 turn is connected by a curved portion 15 of relatively short radius, with a cylindrical gripping portion 17 likewise of short radius.

55 The sheet metal from which my holder is constructed is of sufficient thickness to provide rigidity, while at the same time there

is sufficient "give" to the parts so that when they are brought into operation the best results may be obtained in graining.

60 The pad which I now prefer to use in connection with my holder, is shown at 20 as comprising a sheet of suitable material such as rubber. On the surface of the pad I show curved transversely extending ridges 21. Disposed between these ridges 21, I may 65 provide short longitudinally extending projections 22, some of which may be formed as at 23 into two projections thereby providing greater dissimilarity in the graining surface. 70

75 The transversely extending curved ribs, 21, it will be noted, gradually change from a curve of short radius as at 25 to a curve of a longer radius as at 27, while the remaining curved portions 28 are reversely curved at their inner portion as at 29. Beyond the 80 ends of the portions 21 and 22 I may provide a number of spaced longitudinally extending projections 30. These are preferably arranged to be disposed opposite the curved portion 15 on the plate.

85 Adjacent the two extremities of the graining pad, I may provide transverse ribs 35 which are adapted to be engaged by the ends of the cylindrical portions 11 and 17. These 90 ends 11 and 17 are preferably spaced from the body of the holder a distance somewhat less than the thickness of the pad so that the pad, if made of rubber, may be stretched and inserted in the holder and when released it will immediately spring into engagement with the holder while the ribs 35 will also tend to prevent its removal.

95 Having thus described my invention I claim:

1. In a graining tool, the combination of a member having a curved intermediate portion and a pair of reversely curved end portions and a graining pad secured to the member. 100

2. In a graining tool, a head comprising a strip of material bent to form a curved body portion and two end portions, said end portions being provided with pad engaging means, and a graining pad secured to said engaging means. 105

3. In a graining tool, a holder comprising a strip bent to provide an arcuate portion having curved portions extending from either side of the arcuate portion, said curved portions being spaced from the body of the holder to form a gripping means, said 110

curved portions being spaced from each other and being of unequal size, and a graining pad carried by the holder and having projections thereon.

5. 4. In a graining pad, a body portion, a series of curved transversely extending ribs on the body portion, and a plurality of longitudinally extending projections intermediate the ribs.

10. 5. In a pad for a graining tool, a plurality of transversely extending curved arcuate projections, said projections being of increasing radius from one end of the pad to the other.

15. 6. In a pad for a graining tool, a plurality of transversely extending curved arcuate projections, said projections having their radius increasing from one end of the pad to the other, the projections adjacent one

20. end having their intermediate portions curved reversely to the direction of the main portion of the projection.

25. 7. In a graining tool, the combination of a metal holder and a pad, a plurality of transversely extending curved arcuate projections on said pad, said projections having their radius increasing from one end of the pad to the other, the projections near one end having their intermediate portions

curved reversely to the direction of the main 30 portion of the projection, and a plurality of longitudinally extending projections between said curved projections.

8. In a graining pad, a body portion, said body portion having transversely extending curved projections thereon, relatively short, longitudinally extending projections intermediate said curved projections, a plurality of longitudinally extending projections arranged beyond the end of the 40 curved projections and a transverse rib on said body portion adapted to be engaged by a holder.

9. In a graining tool, the combination of a substantially S-shaped holding member and 45 a graining pad, said member comprising a curved body portion having a reversely curved portion extending therefrom.

10. A graining tool comprising a substantially S-shaped holding member, including 50 a curved body portion and a reversely curved handle portion, said handle portion terminating at a distance from the opposed portion of the holding member to provide a space for the insertion of a graining pad.

In testimony whereof, I hereunto affix my signature.

PAUL A. GSTALDER.
